UNITED STATES PATENT OFFICE.

JACOB CARTUN, OF PHILADELPHIA, PENNSYLVANIA.

INDICATOR.

1,295,121.

Specification of Letters Patent. Patented Feb. 25, 1919.

Application filed June 30, 1916. Serial No. 106,807.

To all whom it may concern:

Be it known that I, JACOB CARTUN, a citizen of the United States, residing at Philadelphia, in the county of Philadelphia and 5 State of Pennsylvania, have invented certain new and useful Improvements in Indicators, of which the following is a specification.

My invention consists of an improved form of indicator, and is especially serviceable for use on motor cars or other vehicles 10 as a signaling device to inform oncoming vehicles of the intention of the driver of the vehicle upon which the indicator is mounted to either turn to the right or left or to 15 stop.

One of the objects of my invention is to provide an indicator of the above described type which may be controlled by the pushing of electrically connected buttons which 20 may be conveniently located adjacent the seat of the driver of the vehicle.

Another object of my invention is to provide means for illuminating the signal and for ringing a bell so as to attract the attention of an oncoming vehicle driver to inform him of the intention of the driver of the vehicle having the indicator thereon to display a signal or that a signal is being displayed.

30 Another object is to so construct my improved invention that the pressing of any one of the electrically connected buttons will operate mechanism to display a respective signal and will also operate to light a lamp and ring the bell.

A still further object is to so design the elements of my invention that they will be simple in construction and easily operated.

These objects, and other advantageous 40 ends which will be described hereinafter, I attain in the following manner, reference being had to the accompanying drawings in which—

Figure 1 is a rear elevation of the principal operating device of my invention shown inclosed in a case with the rear cover of said case removed.

Fig. 2 is a section on the line *a—a* of Fig. 1.

50 Fig. 3 is a face view of a three button switch which I employ.

Figs. 4 and 5 are face views of single point switches which are used respectively to cut out connection between the battery 55 and the lamp and bell.

Fig. 6 is a rear view of the casing shown

in Fig. 5, drawn on a reduced scale, and showing one of the signals displayed as it appears before an opening in the casing, the position of the other signals being shown 60 in dotted lines.

Fig. 7 is a diagrammatic view of the electrically connected elements of my invention.

Referring to the drawings, 1 is a casing 65 made of wood or other material and is so designed as to be readily secured to the rear end of an automobile or other vehicle. This casing has an opening 2 provided with a glass or other transparent member to prevent dust from entering the casing, this opening being of such shape and size as to permit view of any of a number of signaling words or marks, these words as illustrated being Left, Right, and Stop which 70 are painted or otherwise inscribed on a transparent disk or plate 3.

I preferably make this disk by attaching to a small spider or cross arm 4, a series of ribs 5 made of pressed sheet metal or the 75 like, and insert within these ribs 5, a series of transparent celluloid segments 6, 7, 8, and 9.

The segment 6 is blank, while the segments 7, 8, and 9, respectively contain the 80 words Left, Right, and Stop.

The cross arm 4 has secured to it a shaft 10 which is rotatable within bearings 11 secured to the lower end of a vertically positioned solenoid, the latter being secured by 90 a bracket 13 to the upper and inner surface of the casing 1.

The solenoid 12 has an angular core 14 movable therein in a vertical direction when its winding or coil 14^a is electrically energized, and carries a toothed rack 16 which meshes with a pinion 17 on the shaft 10.

The core 14 is provided with a pin 15 which extends transversely therethrough and projects beyond opposite faces 18 and 100 19 respectively. This pin operates with certain elements as will hereinafter be specifically described to limit to different extents the rotary movement of the disk 3.

A standard 20 is mounted on a bracket 21 105 supported on the lower portion of the casing, and this standard 20 is directly below and in the plane of movement of the core 14.

Two levers 22 and 23 are pivoted between 110 their ends to the standard 21, and have hooks 24 and 25 respectively at their upper ends,

the hooked end 25 being at a higher level than the hooked end 24. These levers 22 and 23 are normally held in a substantial vertical position with their hooked ends out of 5 the path of movement of the pin 15, since it will be understood that said latter pin moves upwardly when the solenoid 12 is energized, and also moves downwardly due to gravity and the weight of the core 14 10 when the solenoid 12 is deenergized.

The means for holding the hooked ends 22 and 23 out of the path of said pin consists of a spring 26 which is secured to the standard 20 adjacent its lower end, and 15 presses against the adjacent edges of said hooked levers.

It will be understood that these levers 22 and 23 are respectively positioned adjacent the surfaces 19 and 18 of the core 14, so that 20 the hooked end of the lever 22 may, under certain conditions as shown in Fig. 1, be moved into the path of one end of the pin 15, while the hooked end of the lever 23 may be moved into the path of the other end of 25 the pin 15, so as to arrest or stop the upward movement of the core 14.

The lever 22 below its pivot point is provided with a plate 27, preferably made of iron, and this plate is located adjacent the 30 outer end of an electro-magnet 28 and forms an armature. In like manner, the lever 23 is provided with a plate 29 which is adjacent the outer end of the core of an electro-magnet 30.

35 The magnets 28 and 30 are secured to an insulating board 31 which is mounted on an upwardly extending arm of the bracket 21, this board 31 also forming a support for a main or common binding post 32 as will 40 hereinafter be more fully described in connection with the wiring.

The upper portion of the casing 1 has an electric lamp 33 connected thereto, the bulb of said lamp being in register with the 45 opening 2 in the front face of the casing 1, but is positioned to the rear of the disk 3, so that when the lamp is lighted, its rays will penetrate the celluloid disk and clearly illuminate the latter, so that the indicating 50 signals may be readily seen through the opening 2.

An electric bell 34 is positioned within the casing 1 in a convenient place and will ring when current is passed through the solenoid 55 12 and the magnets 28 and 30.

I provide a selective switch 35 having three push buttons 37, 38, and 39. This switch is connected by three wires 52, 53, and 54 to the lamp, solenoid, and bell respectively. The switch 35 is also connected with a wire 55, said wire 55 being continued to the battery 56 and to the main binding post 32.

The lamp is connected by a wire 57 to the 65 main binding post 32, and the solenoid is

connected by a wire 58 to said main binding post. In like manner, the bell also has a connecting wire 59 which is in electric contact with the main binding post 32.

The switch 35 is also connected by a wire 70 60 to the magnet 30, said magnet also being connected with a wire 61 to the main binding post 32. The plate 47 is connected by a wire 62 to the magnet 28, said latter magnet being connected by a wire 63 to the main 75 binding post 32.

By this construction, it will be understood that the battery 56 is in circuit with all of the electrically operated members, and that by pushing any one of the buttons, the lamp 80 will be lighted and the bell will be rung and the solenoid 12 will also be energized to lift its movable core 14. If the button 37 is pushed, the magnet 28 will be energized, and thereby attract the armature 27 to swing 85 the lever 22 so as to bring its hooked end into the path of the pin 15. On the other hand, if the button 39 is pushed, the magnet 30 will be energized so as to attract the armature 29, and thereby move the lever 23 90 to position its hooked end in the path of the pin 15.

On the other hand, if the central button 38 is pushed, neither of the magnets 28 or 30 will be energized and since their hooked 95 ends are normally out of the path of the pin 15, the movement of core 14 will be unrestricted, and will thereby move to its uppermost position.

The lamp 33 may be thrown out of circuit 100 by the movement of the switch 63 or the bell may be thrown out of circuit by the movement of the switch 64, said switches 63 and 64 being shown open in the diagrammatic view illustrated in Fig. 11. It will be noted, 105 however, that the fact that either the lamp or bell is out of circuit, does not effect the operation of either the solenoid 12 or the magnets 28 and 30.

The parts are so arranged and designed 110 that when neither of the hooks are in the path of the pin 15, the complete upward movement of the core 14, will, through the action of the rack 16 and pinion 17, rotate the disk 3 into such position as to bring the word Stop in register with the opening 2 in the casing. This movement is attained by the pressing of the central button 38, and since the solenoid 12 remains energized as long as the button 38 is held in its inner position, the signal will remain in that position, however, when the button 38 is released to deenergize the solenoid 12, the core 14 will fall by gravity and thereby return the disk 3 to its normal position with the segment 6 115 opposite the opening 2.

The core 14 is limited in its downward movement by a pin 11^a which is secured in the bearings 11 and against which one end of the pin 15 strikes.

If the driver of the vehicle intends to turn to the left, he presses the button 37 which causes the magnet 28 to be energized and swing the hooked end of the lever 22 5 into the path of the pin 15. This movement of the lever is very small, and hence said hooked end moves into the path of the pin before the pin has risen to the level of said hooked end.

10 When the pin reaches the level of the hooked end, it is stopped thereby, and the movement attained by the disk in such upward movement of the pin is sufficient to bring the word Left into register with the 15 opening 2, such position being shown in Figs. 1, 2, and 6 of the drawings. If the driver wishes to display the Right signal, he presses the button 39, and in so doing energizes the magnet 30 to attract its armature 29, and thereby move the hooked end of the lever 23 into the path of the pin 15 to arrest the pin 15 when it reaches and engages said latter mentioned hooked end.

As previously stated, the hooked end of 25 the lever 23 is at a higher level than the hooked end of the lever 22, and therefore a greater movement is attained by the core 14 when the hooked end of the lever 23 is in its path than when the hooked end of the lever 30 22 is in its path, this difference in movement being sufficient to allow the word Left to pass by the opening 2, but to stop the disk when the word Right appears in line with the opening 2.

35 The arrangement of the solenoid 12 in a vertical position permits the free sliding of the core 14 without jamming or producing undue friction, the weight of said core being sufficient to fall by gravity and to turn 40 the disk into a common normal position after each or any of the buttons have been pushed. It will thus be understood that considering that the switches 63 and 64 are closed, if the button 37 is pushed, current 45 will pass from the battery to light the lamp, ring the bell, operate the magnet 28 to move its respective hook to limit the upward movement of the core 14, and the solenoid will be energized to move said core to bring 50 the word Left opposite the opening 2.

In a similar manner, if the button 38 is pushed, the magnets 28 and 30 will remain deenergized but the solenoid will move its core to its uppermost position, and the lamp 55 will be lighted and the bell will be rung. On the other hand, if the button 39 is pushed, the lamp will be lighted, the bell rung, the magnet 30 energized to move its hooked lever, and the solenoid 12 will be energized 60 to move the core to the position permitted by said latter hooked lever.

While I have used the words Left, Right, and Stop as the indicating signals, it will be understood that these may be changed to 65 suit conditions, and while I have described

my invention particularly for use on vehicles and the like, it may be used advantageously any place where it is desired to signal or impart a differential movement to an element such as the disk 3 of my invention. 70

While I have described my invention as taking a particular form, it will be understood that the various parts of my invention may be changed without departing from the spirit thereof, and hence I do not 75 limit myself to the precise construction set forth, but consider that I am at liberty to make such changes and alterations as fairly come within the scope of the appended 80 claims.

Having thus described my invention, what I claim as new and desire to secure by Letters Patent is:

1. The combination of a member having a 85 plurality of signals thereon, unitary means operatively connected to said member and movable a pre-determined distance in one direction to move said member and thereby bring one of said signals into a certain position, and means movable into holding engagement with said first means to stop said movement of the member when another of the signals has reached said position, substantially as described. 90

2. The combination of a member having a 95 plurality of signals thereon, a solenoid having its core operatively connected to said member and movable a pre-determined distance to bring one of said signals into a pre-determined position, a limiting member 100 carried by said core, and selective means movable into the path of said limiting member to stop said movement of the core in different positions so as to stop the other signals when they have reached said position, substantially as described. 105

3. The combination with means having an opening therein, of a member having a plurality of signals thereon, a solenoid having its core operatively connected with said 110 member, limiting means on said core, a plurality of selective members, means for moving any of said selective members into the path of movement of said limiting means and to arrest the movement of said first member in different positions to retain respective signals in line with said opening, substantially as described. 115

4. The combination of a member having a 120 plurality of signals thereon, a solenoid having its movable core operatively connected to said member, a limiting member movable by said core, a plurality of hooked levers, means for normally holding said hooked levers out of the path of movement of said 125 limiting member, armatures carried by each of said hooked levers, electro-magnets adjacent said armatures, and means operative and in electrical connection with said solenoid and magnets to energize said solenoid 130

to move said first member and to energize any of said electro-magnets to move the corresponding hooked lever to limit to different extents the movement of the solenoid core 5 in one direction, substantially as described.

5. The combination of a member having a plurality of signals thereon, a solenoid having its movable core operatively connected to said member, a limiting member movable by said core, a plurality of pivotally mounted hooked levers, means for normally holding said hooked levers out of the path of movement of said limiting member, armatures carried by each of said hooked levers, 10 electro-magnets adjacent said armatures, and means operative and in electrical connection with said solenoid and magnets to energize said solenoid to move said first member and to energize any of said electro-magnets to move the corresponding hooked lever to limit the movement of the solenoid core, the hooked ends of said levers being at different levels to effect the engagement of said limiting member at different positions 15 during the inward movement of the solenoid core, substantially as described.

6. The combination of a member having a plurality of signals thereon, a toothed pinion operatively connected to the member, a toothed rack in mesh with said pinion, a solenoid having its core connected to said rack and movable a pre-determined distance to move one of said signals in operative position, limiting means movable in conjunction 30 with said solenoid core, and means movable to engage said limiting means to stop said solenoid core at different positions within said distance and thereby bring another of said signals in said operative position, substantially as described.

7. The combination of a member having a plurality of signals thereon, a solenoid having a core movable vertically a pre-determined distance in opposite directions, means 45 for operatively connecting said core with said member, and holding means for limiting to different extents the attractive movement of the core by the solenoid, said core being sufficiently heavy to fall by gravity, 50 when the solenoid is deenergized, and thereby move the member in a direction opposite to that of said attractive movement, substantially as described.

8. The combination of a member having a plurality of signals thereon, a solenoid having a vertically movable core operatively connected to said member and movable downwardly by gravity, means for energizing said solenoid, limiting means movable by said core, selective members having armatures thereon, electro-magnets adjacent said armatures, means for energizing said electro-magnets to respectively operate said selective members to limit the upward movement of said solenoid to different extents,

and means for limiting the downward movement of said core, substantially as described.

9. The combination of means having an opening therein, a solenoid having a vertically movable core provided with a toothed 70 rack, a toothed pinion in mesh with said rack, a member having a plurality of signals thereon, any one of which is adapted to be moved in front of said opening, means operatively connecting said pinion with said signal member, a pin in the core of said solenoid, hooked levers having armatures thereon and having their ends at different levels, electro-magnets adjacent said armatures, and electrically connected means operative to energize said solenoid and any of said magnets to move said core and to move any of said hooked members into the path of said pin to limit the upward movement 75 of said core, substantially as described.

10. The combination of means having an opening therein, a solenoid having a vertically movable core provided with a toothed rack, a toothed pinion in mesh with said rack, a member having a plurality of signals 90 thereon, any one of which is adapted to be moved in front of said opening, means operatively connecting said pinion with said signal member, a pin in the core of said solenoid, hooked levers having armatures 95 thereon and having their ends at different levels, electro-magnets adjacent said armatures, and electrically connected means operative to energize said solenoid and any of said magnets to move said core and to move any of said hooked members into the path of said pin to limit the upward movement 100 of said core, and a spring for moving said hooked levers out of the path of said pin, substantially as described.

11. The combination of means having an opening therein, a member having a plurality of signals movable into register with said opening, a solenoid having a vertically movable core, means for operatively connecting said core with said signal member, a pin carried by said core, hooked levers, means for pivoting said levers, armatures on each of said levers, electro-magnets adjacent the armatures, and means in electrical connection with the magnets and solenoid whereby the solenoid is electrically energized and its core is moved to actuate said signal member and any of the electro-magnets is energized to move any of said hooked members 110 into the path of said pin to arrest the movement of said solenoid core in any one of a number of different positions to stop any of said signals when it reaches its registering position with said opening, and means for 115 energizing said solenoid independently of the electro-magnets, substantially as described.

12. The combination in a signaling device, of a member having a plurality of signals 130

thereon, a solenoid having its core operatively connected to said member, limiting means on said core, selective members having armatures thereon, and an electro-magnet adjacent each armature and operative to move its selective member into the path of said limiting member on the core, substantially as described.

13. The combination in a signaling device, 10 of a member having a plurality of signals thereon, a solenoid having a vertically movable core operatively connected to said member, said core being movable within said solenoid when the latter is energized, the core 15 during said movement being operative to move said member and with it to move any of said signals into a pre-determined posi-

tion, said core being sufficiently heavy to move out of said solenoid by gravity when the latter is deenergized and to actuate said 20 member to move any of the signals out of said position, means for limiting said outward movement of the core, and means for stopping the core in different positions during its inward movement to retain respective 25 signals in said position, substantially as described.

In testimony whereof I have signed my name to this specification in the presence of two subscribing witnesses.

JACOB CARTUN.
